UNITED STATES PATENT OFFICE.

HENRY L. TIFFANY, OF SOUTH DARTMOUTH, MASSACHUSETTS.

CONE-TUBE.

1,321,861.

Specification of Letters Patent.

Patented Nov. 18, 1919.

Application filed March 25, 1915. Serial No. 17,035.

To all whom it may concern:

Be it known that I, HENRY L. TIFFANY, a citizen of the United States, and a resident of South Dartmouth, in the county of Bristol and State of Massachusetts, have invented an Improvement in Cone-Tubes, of which the following description, in connection with the accompanying drawings, is a specification, like characters on the drawings representing like parts.

This invention relates to cone tubes adapted to receive or have wound thereon yarn, thread or the like of the commonly known cone winding form and from which the yarn is drawn off axially or substantially so.

In certain aspects thereof, my invention is an improvement upon that shown in the patent to Charles Gess, No. 986,379, dated March 7, 1911.

20 In order that the principle of the invention may be readily understood, I have disclosed a single embodiment thereof in the accompanying drawing, wherein—

Figure 1 is a side elevation of a cone tube embodying my invention;

Fig. 2 is a vertical, central section thereof;

Fig. 3 is a plan view of the tube shown in Fig. 1;

Fig. 4 is a cross sectional view thereof;

30 Fig. 5 is a sectional view of the tip end of the tube;

Fig. 6 is a plan view of the blank from which the cone tube is wound;

Fig. 7 is a side elevation of the upper portion of the cone tube, prior to the inturning of the tip end thereof; and

Fig. 8 is a plan view of the construction shown in Fig. 7.

40 Cone tubes adapted to receive or have yarn or thread wound thereon and from which said yarn or thread is drawn off axially when in upright position are customarily formed of paper rolled in one or more layers or coils into conical form. These tubes are adapted to be mounted for winding upon tapering arbors of the general shape of the tubes and extending through said tube to within an inch or two of the tip end thereof. The ends of these conical tubes 45 generally protrude somewhat from the complete yarn or thread mass. A cone tube of this general character but having an inturned apex end is disclosed in said Gess Patent No. 986,379, and I have represented 50 the disclosed embodiment of my invention as applied thereto.

Referring more particularly to the drawings and to the single embodiment of the invention here illustrated, the blank from which the cone or tube is formed is represented at 1 in Fig. 6, it being preferably of the segmental shape there shown. The said blank is coiled as indicated in Fig. 4 into a suitable number of contacting layers and the inner edges of the said layers should for the best results terminate substantially flush 60 with each other, as indicated at 2 in Fig. 5.

Owing to the fact that the conical tubes are markedly tapering to facilitate the unwinding of the yarn or thread (such tapering materially exceeding that of the usual spinning spindle), it is exceedingly important in effecting the best results that such cone tubes be superficially roughened, thus preventing the slipping or displacement of 70 the yarn or thread as the first series of layers thereof are wound upon the tube and subsequently. This tendency to displacement, particularly of the first laid layers, exists to a marked degree in a cone having a decided 75 taper, but it is nevertheless of importance that the cone tube and the yarn package wound thereon be of decided or markedly tapering form. Such roughening may be of any suitable character, though preferably it 80 is effected by providing the cone tube with longitudinal ridges 3 inclined from top to bottom, such roughening being effected either prior or subsequently to the coiling of the paper or other material into tube form, 85 but preferably while the material is in its flat form. If as prepared the cone tube be superficially roughened, the roughened portion is removed from the tip portion of the tube which, as stated, should present no obstruction to the unwinding of the yarn or 90 thread and especially to the unwinding of the first laid layers thereof.

In order to prevent the first laid coils or layers of the yarn or thread from contacting 100 with the tip end of the cone tube as they are unwound therefrom, the tip end 5 thereof is inturned or upset in any suitable manner, as represented most clearly in Figs. 1, 2 and 5. The tip end of the cone tube 105 should, for effecting the best results, be very materially inturned and preferably so as substantially, if not wholly, to close said tip end, and the inturned end may be turned into the cone tube to any desired extent so 110 as to provide a downwardly extending edge portion.

The tip end of the cone tube, as yarn or thread is being wound thereon, projects very materially beyond the tapered end of the supporting arbor. The approximate position of the outer end of the arbor is indicated by the dotted line $x-x$ in Fig. 2, and is therefore free from contact with the said tip end of the cone tube. It is therefore possible to upset or inturn the tip end 10 of the cone to a very marked degree and so as effectively to prevent the breaking or chafing of the yarn or thread by said tip end as the yarn or thread is unwound.

The cone is markedly conical in order to 15 permit the yarn to free itself from the roughened surface when drawn from the end of the cone and is provided with stiff, cone supporting, side walls to sustain the usually large and heavy package. The tip 20 end of the cone preferably is not only inturned but is smooth, the roughened surface of the body of the cone blending into the smooth, inturned surface of the tip. The said inturned tip end is preferably indifferently 25 centered internally with respect to the axis of the cone, this being possible because the tip end of the cone extends beyond the driver. This is a matter of practical 30 importance, inasmuch as if, in manufacturing the cone, the apex end thereof be somewhat warped or distorted, the fact that the tip end extends beyond the driver permits it to conform in position substantially to the driver, whereby the yarn or thread as 35 drawn off will not be obstructed or impaired by said warped or deflected portion.

In order to prepare the tip end of the cone tube for the inturning action, I preferably 40 first cut or slash the edge of the tip end in any suitable way, after which the tube is subjected to the described inturning action. Within the scope of my invention, this result may be effected in any suitable manner or by any suitable means, and for 45 that purpose I may effect the slashing or cutting by the same mechanism or by a portion of the mechanism by which the tip end is inturned.

In Figs. 7 and 8, I have represented the 50 tip end of a cone tube before the same is inturned and have there represented it as having a series of cuts or slashes 6 extending inwardly from the outer surface of the tube and with a series of cuts or slashes 7 55 extending outwardly from the inner surface thereof and each extending partially through the walls of the cone. Such cuts or slashes may be of any suitable number, and preferably in forming them I remove 60 a small portion of the material of such tip edge, thereby facilitating the subsequent inturning action. If desired, I may also cut or slash the tip edge of the tube wholly therethrough as indicated at 8, such cuts 65 or slashes being preferably alternated with

the slashes 6 or 7. In forming such cuts or slashes 8, I may thereby remove portions of the substance of the wall of the cone. Preferably such cuts or slashes extend to a slight distance from the tip edge toward 70 the base of the cone tube. Preferably subsequent to the cutting or slashing of the tip edge of the cone, I subject such tip end to an inturning action in any suitable manner. This may be effectively done by pressing 75 the tip end against a die, a movement of relative rotation being imparted to the cone tube and die, thereby to effect the described inturning action, and thereby twisting or circumferentially displacing the material, 80 as represented at 9 in Figs. 1 and 3. So far as I am aware, I am the first to provide a cone tube having an inturned end, the latter being cut or slashed or having material removed therefrom to facilitate the 85 inturning action, and therefore desire to claim the same broadly. The inturning of the tip end subsequent to the cutting or slashing of the walls thereof serves to cause contraction of the material at the said points 90 of removal and the extent of the inturning may and preferably is such that at said cuts or slashes when the material is removed, the adjacent transverse edges are brought into contact, so that in the completed article 95 there is presented a smooth tip end notwithstanding said preliminary cuts or slashes.

In accordance with my invention, I may, in addition to cutting or slashing the tip end of the tube, suitably reinforce such tip portion, and if this be done, I desirably accomplish this result by treating the tip portion with some suitable material, such, for example, as sizing or a proper amount of glue. Inasmuch as the tip portions of the 100 cone tubes protrude somewhat from the formed packages, such tip ends are liable to become crushed or somewhat damaged during transportation. Such treatment of the tip end is preferably effected subsequent 105 to the inturning action and after such treatment the cone tube is preferably polished, so that the completed cone tube has a slashed, inturned, treated, polished end, which not only presents no obstruction to 110 the unwinding of the layers of yarn thread, but cannot readily be crushed or damaged in transportation. The sizing or treatment of the tip end, if employed, may extend down to any suitable point.

When the cone tube is in its normal condition,—that is, before the tip end thereof has been inturned,—such tip end is substantially unyielding to inward pressure. When, however, the material of the tube has 125 been circumferentially displaced, then the arch effect existing prior to inturning is materially lost and the twisted portions of the edge, because of their displacement, will more readily yield inwardly. This inturn- 130

ing may be satisfactorily effected by subjecting the inturned end to the action of a die, the die and cone tube having a movement of relative rotation. Such relative rotation 5 of the cone tube and die coincidentally softens the material of the tip end portion, thus enabling it to be turned inwardly and to lie snugly in the die and to receive the smooth, highly desirable, polished surface. Such 10 softening of the tip end renders such tip end less stiff and lacking in rigidity than the body of the tube, it being therefore more pliable and yielding than the body thereof. This, however, renders the tip end liable to 15 be crushed or damaged in transportation and to overcome this I treat the tip end as heretofore set forth and preferably by subjecting it to the action of some suitable material, such, for example, as sizing, by means 20 of which such softening or yielding character is offset or neutralized. In adapting my invention therefore to a cone tube having an inturned end, I preferably apply the stiffening material thereto after the inturning 25 thereof has been effected, thus neutralizing, partially or wholly, the softening action incident to the inturning of such tip end.

The sizing or other material is preferably so applied to the inturned end and subsequent 30 to the inturning action that it neutralizes the softening of the end created by or incident to the inturning action, and therefore the finished cone tube with its inturned end is of substantially uniform stiffness 35 throughout. If desired, I may apply the sizing or other stiffening material in such amount as to result in making the tip end of the cone tube stronger than the body thereof.

40 The cone tube is preferably formed from a segmental sheet of paper pulp, papier mâché or other fibrous material coiled upon itself into a plurality of coils or turns.

Having thus described one embodiment of 45 my invention, I desire it to be understood that although specific terms are employed, they are used in a generic and descriptive sense and not for purposes of limitation, the scope of the invention being set forth in the 50 following claims.

Claims:

1. As an article of manufacture, a winding cone having a yarn-retaining surface markedly conical in shape and a tip end free 55 or exposed when the cone is in condition for use, the tip end of the cone having cuts, facilitating tip-end inturning, said cuts extending wholly therethrough and other cuts extending partially therethrough, said tip end being inturned.

2. As an article of manufacture, a winding cone having a yarn-retaining surface markedly conical in shape and a tip end free or exposed when the cone is in condition for 65 use, the tip end thereof having cuts, facili-

tating tip-end inturning, said cuts extending partially therethrough from the outer surface and other cuts extending partially therethrough from the inner surface, said tip end being inturned. 70

3. As an article of manufacture, a winding cone having a yarn-retaining surface markedly conical in shape and a tip end free or exposed when the cone is in condition for use, the tip end of said cone having cuts, 75 facilitating tip-end inturning, said cuts extending wholly therethrough and cuts alternating therewith, certain of which extend partially therethrough from the outer surface, and certain of which extend partially therethrough from the inner surface. 80

4. As an article of manufacture, a winding cone having a yarn-retaining surface markedly conical in shape and a tip end free or exposed when the cone is in condition for 85 use, the tip end of said cone having cuts, facilitating tip-end inturning, said cuts extending wholly therethrough and cuts alternating therewith, certain of which extend partially therethrough from the outer surface and certain of which extend partially therethrough from the inner surface, said 90 tip end being inturned.

5. As an article of manufacture, a winding cone having a yarn-retaining surface 95 markedly conical in shape and a tip end free or exposed when the cone is in condition for use, the tip end of the cone being cut or slashed to facilitate tip inturning, inturned, reinforced by sizing and superficially polished. 100

6. As an article of manufacture, a winding cone having a yarn-retaining surface markedly conical in shape and a tip end exposed or free when the cone is in condition for 105 use, the material of the tip end being weakened by impairment of the integrity thereof, inturned, reinforced by sizing and superficially polished.

7. As an article of manufacture, a winding cone having a yarn retaining surface markedly conical in shape and a tip end free or exposed when the cone is in condition for use, the tip end of the cone having reinforcing material incorporated into the substance 110 of the cone, said tip end being cut or slashed to prepare it for the subsequent inturning action. 115

8. As an article of manufacture, a winding cone having a yarn retaining surface markedly conical in shape and a tip end free or exposed when the cone is in condition for use, said tip end having incorporated in the substance thereof, a reinforcing material and a portion of the material at the tip end 120 of the cone being removed to facilitate the inturning action. 125

9. As an article of manufacture, a winding cone markedly conical in shape and having stiff side walls adapted to seat upon the 130

rotating drive, said cone when in condition for use having a free or exposed tip end, said tip end having a reinforcement incorporated in the substance of the tip, the material of said tip end being removed at a plurality of spaced points circumferentially thereof to facilitate said tip end being inturned subsequent to the said removal of the material, thereby to cause contraction of the material at the said point of removal.

10. As an article of manufacture, a winding cone markedly conical in shape having stiff side walls adapted to seat upon a rotating drive, said cone when in condition for use 15 having a free or exposed tip end, said tip end having incorporated into the substance thereof a reinforcement, the material of said tip end being removed at a plurality of spaced points circumferentially thereof to 20 facilitate inturning, said tip end being inturned subsequent to the said removal of material, thereby to cause contraction of the

material at said point of removal, said in-turned tip end being polished and presenting no obstruction to the unwinding of the 25 layers of yarn or thread notwithstanding said preliminary cutting or slashing.

11. As an article of manufacture, a winding cone having a yarn retaining surface markedly conical in shape and a tip end free or exposed when the cone is in condition for use, said tip end being impregnated with a reinforcing material, and the apex end of said cone being cut or slashed to prepare 30 said tip end for the subsequent inturning 35 action.

In testimony whereof, I have signed my name to this specification, in the presence of two subscribing witnesses.

HENRY L. TIFFANY.
